UNITED STATES PATENT OFFICE.

REX HARRIS, OF SAN DIEGO, CALIFORNIA.

INTERNAL-COMBUSTION-ENGINE-STARTING MECHANISM.

Application filed April 3, 1924. Serial No. 703,911.

To all whom it may concern:

Be it known that I, REX HARRIS, a citizen of the United States, residing at San Diego, in the county of San Diego and State of

5 California, have invented a certain new and useful Internal-Combustion-Engine-Starting Mechanism, of which the following is a specification.

My invention relates to internal combustion engine starting mechanisms, and the objects of my invention are: first, to provide a mechanism of this class which can be readily connected and secured to an internal combustion engine cylinder for forcing outwardly the piston in the same and simultaneously igniting the gases therein, thus starting the engine; second, to provide a manually operated and automatically controlled mechanism of this class; third, to provide a mechanism of this class in which an explosive cartridge is used to provide the energy for moving the piston outwardly in the cylinder, to which it is connected, and to ignite the gases therein and which is positioned in 10 a chamber separated from the engine cylinder by means of a manually operated valve; fourth, to provide a mechanism of this class in which the trigger mechanism for discharging the cartridge is operated simultaneously with the opening of the valve, thus connecting the cartridge chamber with the engine cylinder; fifth, to provide a mechanism of this class in which the valve and trigger are automatically returned to their 15 original positions when the operating lever is released and after the cartridge has been discharged; sixth, to provide auxiliary trigger releasing means in connection with a mechanism of this class to facilitate the 20 loading of the same; seventh, to provide an adapter for a mechanism of this class by means of which the mechanism may be readily secured to the gas engine cylinder at the spark plug opening or other similar 25 opening therein; eighth to provide a novelly constructed mechanism of this class, and ninth, to provide a mechanism of this class which is very simple and economical 30 of construction, durable, and which will not readily deteriorate or get out of order.

With these and other objects in view, as will appear hereinafter, my invention consists of certain novel features of construction, combination and arrangement of parts 35 and portions as will be hereinafter described in detail and particularly set forth in the

appended claims, reference being had to the accompanying drawings and to the characters of reference thereon, which form a part of this application, in which:

60

Figure 1 is a longitudinal sectional elevational view of my starting mechanism, secured to an engine cylinder, shown fragmentarily, with the section taken through 1-1 of Fig. 2, showing the means in connection therewith for indicating the position of the piston in the engine cylinder and showing by dotted lines certain shifted positions of the hammer and breech block; Fig. 2 is a longitudinal sectional view thereof, taken through 2-2 of Fig. 1, showing certain parts and portions thereof in plan to facilitate the illustration; Fig. 3 is a side elevational view of the cartridge exploding mechanism, separate from the engine cylinder, with certain parts and portions thereof broken away and in section, and Fig. 4 is a transverse sectional view thereof, taken through 4-4 of Fig. 3.

70

Like characters of reference refer to similar parts and portions throughout the several views of the drawings.

80

The barrel 1, adapter 2, engine cylinder 3, gasket 4, cartridge 5, frame 6, breech block 7, pin 8, spring 9, screw 10, hammer 85 11, pin 12, firing pin 13, spring 14, firing pin retaining screw 15, spring 16, spring casing members 17 and 18, pin 19, screw 20, trigger member 21, spring 22, screw 23, valve 24, screw 25, spring 26, washers 27, 90 nut 28, spring 29, spring casing members 30 and 31, screws 22 and 33, pins 34, extractor 35, cam-shaft 36, valve rods 37 and the piston position indicating members 38 and 39, constitute the principal parts and portions of my engine starting mechanism.

95

The barrel 1 is provided at one end with a reduced threaded portion 1^a, which is adapted to be screwed into a threaded recess of the adapter 2, which adapter is also provided with a reduced, externally threaded portion 2^a, which portion is adapted to be screwed into a threaded recess in the wall of the engine cylinder 3. It will be noted that the adapter 2 is used only when the reduced portion of the barrel does not conform with the recess provided in the engine cylinder, and further, that the externally threaded portion of the adapter is made to accommodate the hole already provided in the engine cylinder. It will also be noted that the bore 100 of the barrel, the adapter, and the hole 105

110

through the cylinder wall are in alignment with each other to facilitate the passage of the gases, under pressure, into the engine cylinder. Interposed between the end of the barrel and the adapter is a gasket 4. The bore of the barrel at its opposite or outer end is slightly enlarged to receive the cartridge 5, of special construction, which is retained in position by the breech block 7.

10 The cartridge 5 is provided with a paraffin or similar readily combustible wad to retain the powder therein, which wad is quickly burned up when the explosion takes place. Said outer end of the barrel is also externally threaded to receive and support the frame 6 in which is pivotally mounted the breech block 7 by means of the pin 8. Said breech block is retained in position against the end of the barrel and the cartridge by means of the spring 9, secured within the frame 6 by means of the screw 10. A hammer 11 is also pivotally mounted in the frame 6 by means of the pin 12 extending therethrough and secured in the frame.

15 Said breech block 7 and hammer 11 are so constructed and positioned relatively to each other that the breech block bears against the hammer member and cannot be forced backwardly when the hammer member is forward from its extreme rear position. Nor can the hammer be released and allowed to move forwardly when the breech block is drawn backwardly or disengaged from the rear end of the barrel 1. A firing pin 13 is reciprocally mounted in the breech block 7 and retained therein by the screw 15. The firing pin is retained in a withdrawn position by the spring 14, positioned around the same and between the shoulders within the breech block and on the firing pin. When the hammer member 11 is released, it is forced forwardly, in engagement with the firing pin, by means of the compression spring 16, positioned within the telescoping spring 17, and the member 18 being pivotally connected to the hammer member 11 by means of the pin 19, and the other casing member being pivotally mounted within the frame 6 by means of the screw 20. The hammer member 11 is retained in a backward or cocked position by means of the trigger member 21, reciprocally mounted in the lower portion of the frame 6. The rear portion of the trigger member 21 is reduced and resilient, which permits the same to be forced downwardly or away from the hammer member by means of the downwardly extending pawl portion 11^a on the latter. Said trigger member is further held in engagement with the pawl portion 11^a by means of the spring 22, positioned between the same and the frame and secured to the frame by means of the screw 23. At the rear end of the trigger member is provided an upwardly extending lug 21^a, which actu-

ates or trips the hammer for firing. The lug 21^b, spaced from the end of the trigger member and from the lug 21^a, extends a greater distance from the trigger member, and is adapted to retain the hammer member 11 in a withdrawn or cocked position for recharging the mechanism with another cartridge. The pawl portion 11^a of said hammer member is released from engagement with the trigger member by means of the extended portion 21^c of said trigger member, which portion extends outwardly through the frame 6, and is adapted to be depressed manually. At the opposite end of the trigger member 21 and outside of the frame 6 is provided an upwardly extended portion 21^d provided with a slot 21^e, through which slot extends the screw 25, which pivotally connects the trigger member with the valve 24. The tapered valve 24 is rotatably mounted in and extends transversely through an enlarged portion of the barrel 1, a hole 24^a being provided in the valve to provide a continuous passage from the outer end of the barrel to the engine cylinder. The small end of the tapered valve is reduced, forming a straight portion 24^b, which extends through the wall of the barrel. Around this reduced portion is positioned the compression spring 26 with washers 27 at either end thereof bearing against the barrel and the nut 28, which nut is secured to the end of the portion 24^b for adjusting the tension of the spring 26. The enlarged end of the valve is provided with an outwardly extending lug 24^c, in which is secured the screw 25. Also secured to the valve and extending axially from the enlarged portion thereof is a handle member 24^d, which may be of any desired length and extended in any direction desired by means of universal joints for operating the mechanism from any convenient distance or position. There is further provided at the enlarged end of the valve 24 a lug 24^e, which is adapted to engage pins 34, secured in the barrel, which serve as stops for the open and closed positions of the valve. The valve 24 is held in a closed position, shown in Figures 1 and 2 of the drawings, by means of the compression spring 29, positioned in the telescoping spring casing members 30 and 31, the former being pivotally connected to the frame 6 by means of the screw 32, and the latter casing member being pivotally connected to the lug 24^e by means of the screw 33. Reciprocally mounted in the outer end of the barrel 1 is the extractor 35, as shown best in Fig. 2 of the drawings and by dotted lines in Fig. 3. Said extractor is provided with a downwardly extending portion 35^a, which extends into the recess 7^a of the breech block 7, as shown best in Figs. 1 and 3 of the drawings, the ends of the recess portion engaging the portion 35^a, withdrawing or

forcing the extractor inwardly, for extracting the cartridge after the same has been exploded.

The cam-shaft 36 of the internal combustion engine, which operates the valve rods 37 when the cam-shaft is positioned at the side of the engine frame, is also used to indicate the position of the piston within the engine cylinder prior to starting the engine 10 with my starting mechanism. This starting position of the piston is a position slightly past the top dead center with a charge of combustible gases in the combustion chamber. On the cam-shaft 36 is secured an indicating finger 38, which extends outwardly therefrom, and spaced therefrom and in line therewith when the piston is positioned as stated, is positioned a corresponding indicating finger fixedly secured to the frame of 20 the engine. It is obvious that since the speed of the cam-shaft is one-half the speed of the crank-shaft, as in an engine of the four-cycle type, the indicating fingers 38 and 39 will align with each other once every two 25 strokes of the piston, and when properly secured to the cam-shaft will indicate the proper position of the piston for starting.

It is obvious from the above that when the indicating fingers 38 and 39 are positioned in alignment with each other, and with a cartridge 5 in the chamber of the barrel, the opening 24^a of the valve 24 will align with the bore of the barrel when the handle portion of the valve is turned clockwise, drawing the trigger member 21 outwardly from the frame 6, rotating the hammer member 11 about its pivot, and by the time the opening 24^a of the valve is in alignment with the bore of the barrel 1, the hammer member will be released by the trigger member, permitting the same to spring forwardly to engage the firing pin and discharge the cartridge, permitting the gases to be forced into the combustion chamber of 40 the engine cylinder, forcing outwardly the piston and igniting the gases therein. Immediately, when the handle 24^a is released, the spring 29 will automatically close the valve and force the trigger member 21 into 45 the frame 6, permitting the same to engage the pawl portion 11^a of the hammer member 11.

Though I have shown and described a particular construction, combination and arrangement of parts and portions, I do not wish to be limited to this particular construction, combination and arrangement, but desire to include in the scope of my invention the construction, combination and 55 arrangement substantially as set forth in the appended claims.

It is obvious from this construction that there is provided an internal combustion engine starting mechanism which may be 60 readily connected and secured to an internal

combustion engine cylinder for forcing outwardly the piston in the same and simultaneously igniting the gases therein, thus starting the engine; that there is provided a novel manually operated and automatically controlled mechanism of this class, and a mechanism in which a cartridge is used to supply the energy for moving the piston in the cylinder to which it is connected and is adapted to ignite the gas therein; that there is provided a mechanism of this class 70 in which the trigger mechanism for discharging the cartridge is operated simultaneously with the opening of the valve by which the cartridge chamber is connected with the engine cylinder; that there is provided a mechanism of this class in which the valve and trigger are automatically returned to their original position when the operating lever is released; that there is provided an adapter for a mechanism of this class by means of which the mechanism may be readily secured to any gas engine cylinder at the spark plug opening or other similar opening therein; that there is provided a novelly constructed mechanism of 75 this class, and a mechanism which is very simple and economical of construction, durable, and which will not readily deteriorate or get out of order. 80

Having thus described my invention, what I claim as new and desire to secure by Letters Patent is:

1. In a mechanism of the class described, the combination with an internal combustion engine cylinder of a barrel secured to said cylinder and having a bore communicating with the combustion chamber of said cylinder, a frame secured to the outer end of said barrel, a breech member pivotally mounted in said frame, engaging in its forward position the end of said barrel, a firing pin reciprocally mounted in said breech member, a hammer member pivotally mounted in said frame adapted to engage one end of said firing pin, and a resilient trigger member, reciprocally mounted in said frame, operable from one end and provided with a handle portion at its rear end extending through said frame for releasing said hammer member when the mechanism is loaded. 100

2. In a mechanism of the class described, the combination with an internal combustion engine cylinder of a barrel secured to said cylinder and having a bore communicating with the combustion chamber of said cylinder, a frame secured to the outer end of said barrel, a breech member pivotally mounted in said frame, engaging in its forward position the end of said barrel, a firing pin reciprocally mounted in said breech member, a hammer member pivotally mounted in said frame adapted to engage one end of said firing pin, and a resilient 105

trigger member reciprocally mounted in said frame, operable from one end and provided with a handle portion at its rear end extending through said frame for releasing 5 said hammer member when the mechanism is loaded, and combined means in connection therewith to facilitate the cocking and releasing of said hammer member.

3. In a mechanism of the class described, 10 the combination with an internal combustion engine cylinder of a barrel secured to said cylinder and having a bore communicating with the combustion chamber of said cylinder, a frame secured to the outer 15 end of said barrel, a breech member pivotally mounted in said frame, engaging in its forward position the end of said barrel, a firing pin reciprocally mounted in said breech member, a hammer member pivotally mounted in said frame adapted to engage one end of said firing pin, a valve positioned in said barrel intermediate its ends, means for manually operating said valve, and means in connection with said 20 valve and mounted in said frame in connection with said hammer for releasing the same when said valve is in an open position.

4. In a mechanism of the class described, 30 the combination with an internal combustion engine cylinder of a barrel secured to said cylinder, a frame secured to said barrel, a breech member mounted in said frame, a firing pin reciprocally mounted in said breech member, a hammer member mounted in said frame adapted to engage one end of said firing pin, a valve positioned in said barrel intermediate its ends, means for manually operating said valve, means in connection with said valve and said hammer 35 member for simultaneously opening said valve and releasing said hammer member, and automatic means in connection with said valve for closing the same.

5. In a mechanism of the class described, 45 the combination with an internal combustion engine cylinder of a barrel secured to said cylinder, a frame secured to said barrel, a breech member mounted in said frame, a firing pin reciprocally mounted in said breech member, a hammer member mounted in said frame adapted to engage one end of said firing pin, a valve positioned in said barrel intermediate its ends, means for manually operating said valve, means in connection with said valve and said hammer member for simultaneously opening said valve and releasing said hammer member, automatic means in connection with said valve for closing the same, and means in connection with said engine for indicating the position of the piston of the cylinder to which said barrel is connected.

6. In a mechanism of the class described, 55 the combination with an internal combustion engine cylinder of a barrel secured to

said cylinder, a frame secured to said barrel, a breech member mounted in said frame, a firing pin reciprocally mounted in said breech member, a hammer member mounted in said frame adapted to engage one end of said firing pin, a resilient trigger member reciprocally mounted in said frame, operable from one end and provided with a handle portion at its rear end extending through said frame for releasing said handle when the mechanism is loaded, and a means in connection with said engine for indicating the position of the piston of the cylinder to which the barrel is connected.

7. In a mechanism of the class described, 80 the combination with a gas engine cylinder of an adapter secured to and communicating with the interior of said engine cylinder, a barrel supported by and communicating with said adapter, a frame secured at the opposite end of said barrel, a breech member mounted in said frame adapted to engage the outer end of said barrel, a firing pin reciprocally mounted in said breech member, a hammer member mounted in said frame adapted to engage said firing pin when released, a trigger mounted in said frame for releasing said hammer member, a valve positioned in said barrel, and means for operating said valve.

8. In a mechanism of the class described, 85 the combination with a gas engine cylinder of an adapter secured to and communicating with the interior of said engine cylinder, a barrel supported by and communicating with said adapter, a frame secured at the opposite end of said barrel, a breech member mounted in said frame adapted to engage the outer end of said barrel, a firing pin reciprocally mounted in said breech member, a hammer member mounted in said frame adapted to engage said firing pin when released, a valve mounted in said barrel intermediate its ends, means for operating said valve, and means in connection with said valve and said hammer member for simultaneously opening said valve and releasing said hammer member.

9. In a mechanism of the class described, 90 the combination with a gas engine cylinder of an adapter secured to and communicating with the interior of said engine cylinder, a barrel supported by and communicating with said adapter, a frame secured at the opposite end of said barrel, a breech member mounted in said frame adapted to engage the outer end of said barrel, a firing pin reciprocally mounted in said breech member, a hammer member mounted in said frame adapted to engage said firing pin when released, a valve mounted in said barrel intermediate its ends, means for operating said valve, means in connection with said valve and said hammer member for simultaneously opening said valve and re-

- leasing said hammer member, and means for automatically closing said valve when the means for operating said valve has been released.
- 5 10. In a mechanism of the class described, the combination with a gas engine cylinder of a barrel supported at its one end on said cylinder and communicating with the interior thereof and adapted to receive at its 10 opposite end a cartridge, means for holding said cartridge in position and firing the same, a valve revolvably mounted in said barrel intermediate its ends, means in connection with said valve and said firing means whereby said firing means is released simultaneously with the opening of said valve, and automatic means in connection 15 with said valve for closing the same after the cartridge in said barrel has been exploded.
- 15 11. In a mechanism of the class described, the combination with a gas engine cylinder
- of a barrel supported at its one end on said cylinder and communicating with the interior thereof and adapted to receive at its opposite end a cartridge, means for holding said cartridge in position and firing the same, a valve revolvably mounted in said barrel intermediate its ends, means in connection with said valve and said firing means whereby said firing means is released simultaneously with the opening of said valve, and automatic means in connection 20 with said valve for closing the same after the cartridge in said barrel has been exploded.
